LAWN SPRINKLER

Filed Feb. 25, 1927

Inventor

By L. M. Harland

Attorney

UNITED STATES PATENT OFFICE.

LEWEN R. NELSON, OF PEORIA, ILLINOIS.

LAWN SPRINKLER.

Application filed February 25, 1927. Serial No. 170,758.

This invention relates to lawn sprinklers, being directed particularly to the spray nozzle type.

While adapted for general use as a lawn 5 sprinkler the device herein to be described is particularly fitted for irrigating large areas where a number of them are connected with a piping system buried below ground as is customary in Western Coast States.

10 Objects of the invention are to provide a spray nozzle of a very efficient form in the matter of wide and even water distribution; a nozzle that can be quite easily adjusted for distance of water-throw; and one not likely 15 to cause trouble or require attention after being set for use.

Another object is to provide a spray nozzle 20 of a type of construction that will admit of its being made almost entirely of formed sheet metal through stamping operations whereby a large production at low cost is possible, and where accuracy of manufacture can be maintained so that the parts can be readily interchanged to the end that replacement of 25 parts is rendered easy.

For the ready and complete understanding of the structure of my spray nozzle the accompanying drawing has been provided 30 wherein:

30 Figure 1 is a side elevation of a spray nozzle in which the invention is involved.

Figure 1^a is a section, in perspective, of part of the body of the device taken on line 1—1^a, Figure 1.

35 Figure 2 shows the spray nozzle as seen at its under side.

Figure 3 is a vertical section of the device in its completely assembled form.

40 Figure 4 is a vertical section of portions of certain parts shown in Figure 3.

Figure 5 is a plan of a diaphragm shown in Figures 3 and 4, and

45 Figure 6 is a transverse section of part of said diaphragm.

With the end in view of producing a spray 50 nozzle the parts of which can be readily interchanged or replaced easily made, together with extreme accuracy of manufacture, I prefer to produce the parts of the nozzle by stamping them from sheet metal. In the drawing, therefore, the character 1 designates as a whole the main body of my 55 nozzle which includes a tubular internally threaded neck 2 adapted to be screwed upon a water supply pipe 3, Figure 1, said neck having formed on its extremity a flange 4

flattened at opposite sides, for example, as 5, to receive a suitable wrench indicated at 6 in Figure 2. Also the body includes an expanded bell shaped portion 7 surmounting the neck 60 2, the whole being stamped from sheet metal in a customary way. Exteriorly the body at its top edge, as viewed in Figures 3 and 4, is provided with screw-threads 7' for a purpose 65 to appear.

As indicated in Figures 1 and 2, lugs or fins 7^a are formed in the wall of the body to extend therefrom in positions about as shown in said Figure 2, for example. The location of the fins forms a grip for the hand whereby the 70 body may be adjusted upon the pipe 3 and also that the wrench applied to the flattened portions of the flange 4 may also engage one or more of said fins as suggested by broken lines in Figure 1.

75 Within the body is a portion which comprises a bell shaped stamping or shell 8 whose edge at its widest portion has an annular flange 9 to rest upon the free edge of the body 1 as most clearly shown in Figure 4, said 80 stamping having a cylindrically formed portion 10 closed at its end as 11, there being ports 12 in the portion as shown in Figure 3.

Seated in said cylindrically portion in a snug 85 working fit is a plug 13, constituting a valve which is cavitated, the upper end being closed and shouldered at that end as at 14 and having a reduced head 15 grooved at 16 for example to receive a screw driver or similar tool. The plug is provided with ports 17 adapted to 90 register with the ports 12, and it also has ports 18 opening into the space of the bell portion of the shell or stamping. When the described parts are assembled the shoulder 14 preferably extends beyond the plane of the 95 top surface of the flange 9 of the stamping 8 as shown in Figure 4. A diaphragm 19, Figure 5, having a central aperture 20 lies upon said shoulder 14 and due to the position of the latter in the respect named is spaced slightly 100 from the flange 9 as in said Figure 4. The diaphragm, at positions about its central point, is provided with ports 21 created by partially severing the metal at those positions and forcing it out of the plane of the metal as 105 in Figure 6, this, of course, being an old and well known procedure.

To complete the nozzle a cap 22 is now provided which has a central depressed portion 23 provided with an aperture 24. Also, the 110 cap during its formation is furnished with a shoulder 25, interiorly, to engage upon the

marginal edge of the diaphragm 19 and includes an interiorly threaded skirt portion 26 to screw upon the body 1, the same terminating in a flange 27 which is shaped to take 5 a wrench whereby said cap may be firmly screwed in place. In screwing the cap down to position the shoulder 25 thereof engages upon the diaphragm, springing that member, and clamping its marginal edge upon the 10 flange 9 of the shell or stamping 8. This action results in causing the diaphragm to maintain constant pressure upon the plug 13 holding the latter firmly in its seat together with the fact that the plug will remain 15 in any position to which it may be adjusted due to frictional engagement of the parts, it being understood that a suitable tool inserted through the aperture 24 of the cap may be used to adjust the plug by engaging the slot 20 or groove 16 of that member.

In action, the water enters the neck 2, passes through the ports 12 and 17 into the plug and out through the ports 18 thereof into the cavity of the shell 8. In passing through the 25 ports 21 of the diaphragm the water takes up a whirling motion due to the position of said ports and finally issues from the aperture 24 of the cap in a funnel-shaped spray.

Particularly where a number of spray 30 nozzles are used on a single pipe system as is practiced in some sections of the country, the adjustment of the plug 13 provides for limiting the flow of water from the nozzle nearest the source of pressure in said system, the 35 plug of each succeeding nozzle as it lies farther from the source of pressure being left slightly wider open until at the position farthest from the said source the ports are left wide open. This, it may be seen, provides for an even distribution of the water over the 40 area being irrigated. As a matter of fact those nozzles lying most remote from the pressure source may not include the shell 8 and the plug, but merely consist of the body 1, and the diaphragm 19 and cap 22. In the 45 latter event, of course, the central opening 20 of the diaphragm would be lacking since not required to receive the head 15 of the plug.

I claim:

50 1. A spray nozzle comprising a hollow body, a shell portion therein including a seat, a hollow plug rotatably mounted in said seat, the shell having a port opening from the cavity of the body, and said plug having a port to register with that of the shell, the bore of said plug communicating with the cavity of the shell, a diaphragm seated in the shell closing its cavity and having ports therein and resting on the plug holding it in its seat, and a 55 cap provided with a discharge opening and engaging the body and diaphragm whereby to clamp the latter and the shell to the body.

60 2. A spray nozzle comprising a hollow body, a shell portion therein including a seat, a hollow plug rotatably mounted in said seat,

the shell having a port opening from the cavity of the body, and said plug having a port to register with that of the shell, the bore of said plug communicating with the cavity of the shell, a diaphragm seated in the shell closing its cavity and having ports therein and resting on the plug holding it in its seat, said plug having an extension projecting through the diaphragm, and a cap provided with a discharge opening opposite the plug and screw threaded on the body engaging the diaphragm whereby to clamp the said diaphragm and the shell to said body. 70

3. A spray nozzle comprising a hollow body for attachment to a water supply pipe, so a separate shell portion resting on the body and suspended within the same and having a cylindrical seat provided with a port, a cavitated plug rotatably mounted in said seat and having a port in its wall to register with that of the shell, said plug being open to the cavity of the shell distant from the port and shouldered, a cap engaging the body and having a discharge opening and a diaphragm including ports clamped between the shell 90 and the cap and bearing upon the shoulder of the plug, the latter extending above the shoulder through said diaphragm.

4. In a spray nozzle, a hollow body, a separate shell therein closed to the cavity thereof but including a port, a cavitated rotatable plug in said shell having a port to register with that of the shell, the cavity of the said plug opening into the cavity of the latter, said plug having a shoulder and an extension at 100 its end opposite that having the port, an apertured diaphragm having an opening to receive the extension resting upon said shoulder, and a cap engaging the body and having an outlet, said cap engaging the margin of the diaphragm clamping the same and the shell upon said body. 105

5. In a spray nozzle, a hollow body, a separate inner shell including a seat portion to receive a plug, said portion having a port but otherwise closed to the cavity of said body, said shell including a flange supported on the body, a cavitated plug rotatable in said seat including a port adapted to register with the first named port, the cavity of the plug communicating with the cavity of the shell, an apertured diaphragm adapted to lie at its margin upon the flange of the shell, said plug extending through the diaphragm and shouldered beneath and adapted to receive 120 the latter upon it, and a cap engaging the body and clamping the diaphragm and shell upon the same, said cap having a discharge opening disposed opposite the plug. 115

6. A spray nozzle including in its construction a shell portion open at one end and at its other end terminating in a hollow cylindrical portion of relatively smaller diameter having an aperture in its wall, a cavitated plug seated at one end in said cylindrical portion, 125 130

- being rotatable therein and having a port in its wall to be brought into register with said aperture, said plug remote from its port being exposed within the shell portion, its cavity 5 communicating with the space of said shell portion, a diaphragm closing the open end of the shell and having an opening therethrough, the plug extending through said opening closing the same and shouldered beneath the diaphragm to receive the latter upon it, and said diaphragm also having an opening therethrough communicating with the cavity of said shell.
7. A spray nozzle including in its construction 15 a hollow body of drawn metal interiorly threaded at one end and formed with a turned flange at that end flattened on its edges at two opposite positions adapted for receiving a wrench, said body being outwardly flared toward its other end and externally threaded, a shell of drawn metal depending within the body including a turned flange to rest upon the flared end of said body and including a cylindrical extension forming a seat, a 20 25 cavitated rotatable plug fitting said seat, its cavity opening into the cavity of the shell, said plug and seat each having a port adapted to register with one another, an apertured diaphragm seated on the shell and said plug, the latter extending through said diaphragm, and an apertured cap of drawn metal engaging the threads of the body adapted to engage the margin of said diaphragm whereby to clamp the latter and the flange of the shell 30 35 upon said body, said cap having a flange having flattened faces adapted to receive a wrench.
8. A spray nozzle including in its construction 40 a hollow member having at one end a seat provided with a port, a cavitated plug rotatable in the seat having a port to register with that of said seat, the cavity of the plug communicating with the cavity of the member, said plug extending outside the plane of the member at one end, an apertured diaphragm engaging upon the plug and at its marginal edge adapted to bear on the said end of the member, a body and a part to screw on the body and engaging the diaphragm clamping the 45 50 55 said marginal edge of the same and the member upon said body.
9. A spray nozzle including in its construction 55 a hollow member having a seat in one portion thereof provided with a port, an apertured diaphragm whose marginal edge is adapted to lie upon a portion of the member spaced from said seat, a body receiving the member and diaphragm, means on the body
- to engage the diaphragm to clamp it and the member upon said body, and a cavitated plug 60 interposed between the seat and the portion to which the diaphragm is clamped and rotatable in said seat, the cavity of the plug communicating with the cavity of the member.
10. A spray nozzle including in its construction 65 a cavitated body, a hollow member depending into the body and having a marginal portion to rest on the body and also having a seat in one portion thereof provided with a port, an apertured diaphragm whose 70 75 marginal edge is adapted to lie upon the said marginal portion of the member and spaced from said seat, means on the body to engage the diaphragm for clamping it and the member together upon said body, and a cavitated plug interposed between the seat and the portion to which the diaphragm is clamped and rotatable in said seat, the cavity of the plug communicating with the cavity of the member, and said plug including a part extending 80 85 through the diaphragm and fashioned to receive an operating tool.
11. A structure as part of a spray nozzle consisting of a shell open at one end and having an outer marginal flange, said shell being contracted at its other end and formed into a cylinder, a tubular member fitting into and rotatable within said cylinder opening through the same, said member having an opening within the shell distant from the 90 95 cylinder and shouldered, one of the parts being formed to prevent relative movement of the member other than a rotary one, and, a diaphragm seated upon both the marginal flange and the shoulder of the member closing the cavity of said shell.
12. A structure as part of a spray nozzle consisting of a shell open at one end and having an outer marginal flange at that end, said shell being contracted at its other end and formed into a cylinder closed at its outer end, a tubular member seated at one end in the cylinder fitting the same and having a shoulder, there being an opening through the cylinder wall, there also being an opening in the 100 105 110 wall of said member adapted to register with that of the said cylinder, a perforated diaphragm seated on both the said marginal flange and the shoulder of the member, the latter extending through said diaphragm, there being an opening in the wall of the member between the cylinder and the said diaphragm, the member extending through the latter outward from the said shoulder.

In testimony whereof I affix my signature.
LEWEN R. NELSON.
